UNITED STATES PATENT OFFICE.

GEORGE HENRY WHEARY, OF RACINE, WISCONSIN.

LOCKING MEANS FOR TRUNK DRAWERS.

1,419,594.

Specification of Letters Patent. Patented June 13, 1922.

Application filed May 19, 1920. Serial No. 382,484.

To all whom it may concern:

Be it known that I, GEORGE HENRY WHEARY, a citizen of the United States, and resident of Racine, in the county of Racine 5 and State of Wisconsin, have invented new and useful Improvements in Locking Means for Trunk Drawers, of which the following is a description, reference being had to the accompanying drawings, which are a part of 10 this specification.

This invention relates to improvements in locking means for trunk drawers.

Wardrobe trunks of the better class are usually divided vertically into two parts to 15 form a wardrobe section and a drawer section. The two parts are hinged together to swing horizontally to open or closed position, and one section is provided with garment hangers for suspending outer wearing 20 apparel thereon, and the other section is provided with drawers for holding other articles of wear. In order to guard against the drawers moving inwardly and outwardly during transportation to the damage or in 25 jury of the drawers a locking mechanism is desirable and necessary.

It is one of the objects of this invention to provide a simple and convenient form of lock which is adapted to lock all of the 30 drawers in closed position.

A further object of the invention is to provide a locking means for trunk drawers which is formed in two sections to permit the easy handling of the parts.

35 A further object of the invention is to provide a locking means for trunk drawers in which all of the drawers of the drawer section may be locked by a single lock, and also tie and reinforce the vertical walls of the 40 drawer section.

A further object of the invention is to provide a locking means for trunk drawers which is of simple construction, is strong and durable and is well adapted for the pur- 45 pose described.

With the above and other objects in view, the invention consists of the improved locking means for trunk drawers and its parts and combinations as set forth in the claims, 50 and all equivalents thereof.

In the accompanying drawing in which the same reference characters indicate the same parts in all of the views:

Fig. 1 is a front view of a portion of the 55 drawer section of a wardrobe trunk provided with the improved drawer locking means;

Fig. 2 is a vertical sectional detail view of the upper portion of the trunk section taken on line 2—2 of Fig. 1 and on a larger scale, the upper part of the locking bar being 60 shown in its inner position;

Fig. 3 is a similar view of a medial portion of the trunk taken on line 3—3 of Fig. 1;

Fig. 4 is a detail perspective view of a 65 medial securing means, a portion of the bar being indicated by dotted lines; and

Fig. 5 is a detail perspective view of lower end portion of the locking bar securing means, a portion of the bar being indicated 70 by dotted lines.

Referring to the drawing, the numeral 8 indicates the drawer section of a wardrobe trunk provided with a plurality of drawers 9 slidably supported upon angled rails 10 75 mounted within the trunk section. The drawers are provided with suitable pull handles 11 for convenience in opening the drawers. Side portions of the drawer section are reinforced and connected together 80 by transverse bars 12 and to the lower sides of these bars are mounted outwardly extending slotted arms 13. The slots 14 are of elongated form transversely of the arms and the entrance openings 14' to said slots are of 85 less length than the slots 14.

Secured to and projecting outwardly from the bottom portion of the drawer section is another arm 15 which is provided with an elongated opening or eye 16 extending vertically therethrough for receiving the lower reduced end portion 17 of a lower part drawer locking bar 18 which is adapted to be positioned in front of some of the drawers. In order to engage the slotted 95 arms 13 medial opposite edge parts of the bar are cut away to form locking portions 19 of less width than the other portion to permit the bar to be easily entered into the elongated slots of the arms when the bar is 100 raised above its normal position of rest as shown in Fig. 1. When inserted and lowered the opposite side edge portions of the locking bar will be locked by the shoulders 20 formed by the elongated slots 105 14 and the openings 14' of less width. A pin 21 projecting outwardly from the lower end portion of the bar 18 rests upon the arm 15 and limits the downward movement of the bar.

The upper end portion of the bar 18 is bent inwardly and downwardly at right angles

to form a hook and lock portion 22 which is provided with a top bolt opening 23 and a side pin opening 24 for receiving respectively, a spring bolt 25 and a holding pin 26 which are carried by the upper part locking bar member 18'. Said upper bar part 18' is formed with an upper end inwardly and downwardly extending hook portion 27 which hooks over an eyed arm 28 mounted in the upper portion of the drawer section and projecting outwardly therefrom. Said arm is of tubular construction to permit the bar part 18' to be pushed inwardly into said tubular portion when unlocked and swung upwardly. The lower end portion of the upper part bar overlaps the upper end portion of the lower part bar and the holding pin 26 rigidly connected to said upper part extends into the side pin opening 24 of the lower part bar. The spring bolt 25 forms part of the lock 29 mounted on the inner face of the upper part bar member 18 and is formed with an inner beveled face 25' so it will automatically snap into the opening 23 of the locking part 22 when the upper bar is hooked to the eyed arm 28 and swung inwardly to closed position.

The upper drawer adjacent the lock is provided with a recessed portion 30 having a front shoulder 30' to accommodate the lock and the locking part 22 of the lower bar part and prevent said lock from swinging outwardly. The lock 29 is controlled by a key 31 in the ordinary manner.

35 In use the two part locking bar extending in front of the medial portions of the drawers and connected to the trunk section at its opposite ends and intermediate of its ends securely locks the drawers in closed position, 40 and when it is desired to gain access to the drawers it is only necessary to unlock the bolt, swing the upper part bar outwardly and then raise slightly to disengage it from the eyed arm to permit its removal. The 45 lower part bar may then be removed by raising vertically to register its narrow portions with the slotted arms and swing outwardly. In locking the reverse operation takes place with the exception that it is not 50 necessary to use the key as the bolt will snap to closed position.

From the foregoing description it will be seen that the locking means for trunk drawers is of very simple construction, and is well 55 adapted for the purpose described.

What I claim as my invention is:

1. The combination with a trunk section having drawers, of a means for locking said drawers in closed position, comprising arms 60 projecting from upper and lower and intermediate portions of the trunk section, a locking member formed of two independent parts removably engaging all of said arms, the adjacent ends of said two part locking member removably overlapping each other, and

means locking the overlapped portions together.

2. The combination with a trunk section having drawers, of a means for locking said drawers in closed position, comprising eyed 70 arms projecting from the upper and lower portions of the trunk section, a slotted arm projecting from the medial portion of the trunk section, a locking bar formed of two independent parts engaging the eyed arms 75 and the slotted arm and having its adjacent ends removably overlapped, and means locking the overlapped portions together.

3. The combination with a trunk section having drawers, of a means for locking said drawers in closed position, comprising eyed 80 arms projecting from the upper and lower portions of the trunk section, a slotted arm projecting from the medial portion of the trunk section, a locking bar formed of two 85 independent parts engaging the eyed arms and the slotted arm and having its adjacent ends overlapped and removably pinned together, and means locking the overlapping portions together, one of the bar parts when 90 unlocked being slidably movable into the upper portion of the trunk section.

4. The combination with a trunk section having drawers, of a means for locking said drawers in closed position, comprising eyed 95 arms projecting from the upper and lower portions of the trunk section, a slotted arm projecting from a medial portion of the trunk section and having a narrow entrance opening to the slotted portion of the arm, a two part locking bar having a hooked engagement with one of the eyed arms and a slidably engagement with the other two arms, and means locking the adjacent ends 100 of the two part bar together.

5. The combination with a trunk section having drawers, of a means for locking said drawers in closed position, comprising eyed 105 arms projecting from the upper and lower portions of the trunk section, a slotted arm projecting from a medial portion of the trunk section and having a narrow entrance opening to the slotted portion of the arm, a two part locking bar having a hook formed 110 on its upper end which engages the upper eyed arm, the lower end portion of the arm slidably entering the lower eyed arm, a medial portion of the bar being of less width than other portion to permit the bar to lockingly enter the elongated slot of the slotted arm, and means for locking the adjacent ends of the two part bar together.

6. The combination with a trunk section having drawers, of a means for locking said drawers in closed position, comprising eyed 115 arms projecting from the upper and lower portions of the trunk section, a slotted arm projecting from a medial portion of the trunk section and having a narrow entrance opening to the slotted portion of the arm, 120

a two part locking bar having a hook formed on its upper end which engages the upper eyed arm, the lower end portion of the bar slidably entering the lower eyed arm, a 5 medial portion of the bar being of less width than other portion to permit the bar to lockingly enter the elongated slot of the slotted arm, one of the upper end portions of the lower part of the two part bar extending inwardly and having a bolt opening in its upper portion and a pin opening in its front part, the lower end of the upper part of the bar having a projecting pin which enters the pin opening, and a lock mounted on the 10 lower end portion of the upper part bar and having a bolt which enters the bolt opening.

7. The combination with a trunk section

having drawers, of a means for locking said drawers in closed position, comprising eyed arms projecting from the upper and lower 20 portions of the trunk section, the upper of said arms being of tubular form, a slotted arm projecting from the medial portion of the trunk section, a locking bar formed of two independent parts engaging the eyed 25 arms and the slotted arm and having its adjacent ends overlapped and removably pinned together, and means locking the overlapping portions together and to one of the trunk drawers, the upper bar part when unlocked being slidable into the upper tubular arm.

In testimony whereof, I affix my signature.
GEORGE HENRY WHEARY.
